US0D1071602S

(12) United States Design Patent (10) Patent No.: US D1,071,602 S
(45) Date of Patent: * Apr. 22, 2025

(54) SANITARY FLUID DISPENSER

(71) Applicant: ADA Cosmetics International GmbH, Kehl/Baden (DE)

(72) Inventors: Johannes Schmidt, Kehl/Baden (DE); Mitja Cepin, Šenčur (SI)

(73) Assignee: ADA Cosmetics International GmbH, Kehl/Baden (DE)

() Term: 15 Years

(21) Appl. No.: 29/901,253

(22) Filed: Aug. 30, 2023

Related U.S. Application Data

(62) Division of application No. 35/515,013, filed on Apr. 11, 2022 (U.S. filing date under 35 U.S.C. 384), and having an international filing date of Apr. 11, 2022, now Pat. No. Des. 1,006,484.
